EDWARD F. COLLADAY, OF WASHINGTON, DISTRICT OF COLUMBIA.

WAVE-TRANSFORMATION SYSTEM OF RADIO BROADCAST DISTRIBUTION

Application filed February 9, 1924. Serial No. 691,821.

My invention relates to radiophone exchange systems and has for its object to simplify and improve methods of controlling the broadcast distribution of intelligence.

5 Briefly stated, the invention comprises a radio-wire system, in which two sets of waves are radiated at different frequencies, and both sets are received at each subscriber's station, and the combined or resultant potentials 10 are impressed upon the subscriber's circuit, whereby electrical variations of a frequency equivalent to the mean between the two primary frequencies, will be produced in the subscriber's line to central. At the central station 15 end of the line, a detector, with or without amplifiers, (both radio and audio), receives the radio oscillations, detects and rectifies the same, and returns corresponding audio frequency waves over the line to the 20 subscriber's station, where they are rendered intelligible by suitable receiving apparatus, not responsive to the primary waves. The electrical variations in the line may be amplified by passing through a tube or tubes, 25 that is to say, in one or more stages, at the central station, and sent back over the line thus amplified, to be picked up by the subscriber, and rendered audible at his station in the usual way.

30 Certain advantages inhere in the arrangement described. One is in respect to the simplicity of line connections, since all radio transmission is through the ether, and the only terminal attachments necessary are multiple taps across the lines, each containing the tuning elements, and one coil of a coupler. At both ends of the line, these are the only elements that need physical attachment thereto, and the tuning is such that audio telephone currents or battery currents are 40 entirely unaffected thereby. Another advantage at the central office is the concentration of detector tubes and circuits at central with the battery supply where constant inspection and care are rendered easy and simple.

45 This system is intended to be used for distant receiving and distribution or for local broadcasting. For distant receiving the central office apparatus includes a tuned receiving antenna circuit and a relay transmitter,

which sends out the same radio waves amplified; also a local heterodyning transmitter with a properly tuned aerial. The modulations in this case are carried on the relayed waves, and the local heterodyne waves may 55 be unmodulated. Where local broadcasting is desired however, a second modulated local oscillator circuit is provided, which takes the place of the relay transmitter for distant waves. Thus with two local oscillators, it 60 follows that either train of waves may be modulated, and this affords means to give out local programs limited to the subscribers only, without interfering with individual subscribers' reception of distant stations 65 when practiced with independent apparatus.

70 My invention is illustrated in the accompanying drawing, in which the figure is a diagram showing a central station CS and a subscriber's station SS. At the central station are indicated a radio receiving and relaying apparatus RR and local oscillator LO. The radio relaying apparatus RR has a tuned antenna circuit 1, the local oscillator has a 75 tuned antenna circuit 2. It is quite obvious that interference between these trains of waves can produce no ill effect, since they are intended to heterodyne at the subscriber's station and in the subscriber's wired line circuit. At the subscriber's station 3 is one antenna circuit tuned to the frequency transmitted by the radio relay RR, and 4 is a similar antenna circuit tuned to the frequency of the central office local oscillator LO. If it be desired to avoid tuning entirely at the subscriber's station, it may be done in the following manner: Provide the radio relay set RR with either audio or radio means (such as a primary heterodyne circuit) to change the frequency of the modulated waves received 80 from distant stations over the antenna 1, so that they will always go out locally on a constant wave length. In such case, the local oscillator LO would also be tuned for a constant wave length, and it necessarily follows 85 that the tuning of the subscriber's antennæ 3 and 4 may then be for constant wave length, as well as any local resonating circuit connected therewith.

90 At the subscriber's station I have shown 100

- the usual telephone set TS and a jack J bridged across the line to receive a plug P constituting the terminal of a local receiving circuit RC containing the telephone receiver TC and talking condenser AC, the purpose of this being to prevent closing the line for battery current while listening to the relayed and amplified audio current coming from central.
- 5 10 At the central station J'-J' represent the ordinary standard switchboard terminals of any desired type, to which the line 5-6 is connected for telephone communication with the subscriber's station SS. The dotted lines 15 in the middle of the figure represent that portion of the line which extends between the subscriber's station and the central office. Across the ends are bridged elements I-I' and VC-VC', and coupler coils CC and CC'. 20 Coupled through coils C and CC is the local circuit 7, containing a detector tube 7^a of standard type, the grid circuit of which is adapted to be affected by the electrical variations on the line, and to produce signal currents in the plate circuit, which is inductively connected through the audio transformer AT across the line, thus feeding back audio frequency waves at audio frequency to the subscriber's line, where they become intelligible in the receiving instrument TC or 30 its equivalent. It is obvious that any desired number of stages of radio frequency amplification, or audio frequency amplification may be inserted before and after the detector tube 7^a, and it should also be observed that the lines may be connected through the coupler coils CC to bus circuits and served by tubes 7^a or the equivalent, which are common to a plurality of lines. This is possible 35 40 because all the lines taking the service are receiving the same signals. Neither would this prevent selection of programs, which is very desirable.

What I claim is:

- 45 In a system of radio broadcast distribution, a central station and subscribers' stations and wired circuits interconnecting them, means at the central station to relay modulated radio waves received from a distance over the local area, means to transmit 50 heterodyne frequencies therefor over the same area, collector means at the subscribers' stations for receiving both the modulated and the heterodyne waves, coupling means to impress said waves simultaneously on the subscribers' wires, means at the central office connected to said wires to produce resultant modulated waves due to said modulated and heterodyne waves in the line wires, and to 55 60 amplify the same, and means at each subscriber's station to receive and render audible said amplified waves.

In testimony whereof I hereunto affix my signature.

EDWARD E. CLEMENT.
